HOMER HASTING,

By *Homer H. Hastings*,

Attorney

UNITED STATES PATENT OFFICE

HOMER HASTING, OF DETROIT, MICHIGAN.

CARTRIDGE.

1,263,763.

Specification of Letters Patent. Patented Apr. 23, 1918.

Application filed October 26, 1917. Serial No. 198,723.

To all whom it may concern:

Be it known that I, HOMER HASTING, a citizen of the United States, residing at Detroit, in the county of Wayne and State of Michigan, have invented new and useful Improvements in Cartridges, of which the following is a specification.

This invention relates to electrically discharged cartridges and ammunition and pertains particularly to an improved form of cartridge providing positive electrical discharges or sparks in the mass of powder.

One object of the invention is to provide an electrically discharged cartridge having a plurality of spark gaps.

Another object of the invention is to provide an electrically discharged shell in which there is no detonator or primer substance needed and in which the main and only charge of explosive is packed around the spark gaps.

Another object of the invention is to provide an electrically discharged cartridge in which there is provided a novel removable butt end having a screw threaded connection with the main casing.

A further object of the invention is to provide an electrically discharged cartridge in which an insulating block of nonconductive material is tapered and adapted to fit into a corresponding tapered opening in the butt end.

The above and other details and advantages of the construction will be described and claimed in the following specification and claims and illustrated in the accompanying drawing in which:

Figure 1 represents in partial longitudinal section the construction of the cartridge assembly.

Fig. 2 represents the butt end of the cartridge showing the insulated block portion and the outer end of the electrodes.

Fig. 3 represents the construction shown in Fig. 1, with the butt end unscrewed from the casing.

Fig. 4 represents the same type of butt end construction adapted for use in a tapered casing.

Fig. 5 represents a form similar to that shown in Fig. 4 but with an annular space between the end of the casing and the butt end.

Fig. 6 illustrates diagrammatically the electrical circuit used in connection with the cartridge.

Referring in detail to the construction of the cartridge illustrated in the various figures, 1 indicates a tubular cartridge casing having the central bore 2. This casing is formed of electrically conductive material such as the usual brass or copper cartridge casing. At the butt end or breech end of the casing 1 there is provided screw threads on the surface of the inner wall. A butt end member 3 having the annular rim 4 is provided with screw threads 5 adapted to be engaged with the screw threads of the casing 1. The butt end member 3 is likewise formed of electrically conductive material. The butt end member 3 is provided with a centrally located opening extending through the thickness of the butt end member and is tapered flaring inwardly toward the bore of the casing. A complementary tapered insulating plug 6 is provided with screw threads 7 and is adapted to be seated in the opening in the butt end member 3 and have a screw threaded engagement with corresponding screw threads provided on the wall of the opening. By forming the opening and the shape of the plug 6 so as to locate the larger end of the plug 6 on the inside of the cartridge, any weakening of the construction by explosions is prevented, each additional discharge or use of the cartridge forcing the plug tighter within its retaining walls. Extending through the insulating plug 6 and axially of the same is a centrally located electrode member 8, terminating substantially flush with the insulating material 6 on the outside end of the shell or cartridge and projecting on the opposite side well into the bore 2. A second electrode member 9 extends in a similar way through the insulating plug 6 and projects into the bore 2. This electrode 9 however has a recurved end portion 9^a extending across the end of the electrode 8 and terminating in close proximity to the inner wall of the casing 1. By this construction a double spark gap is provided between the portion 9^a and the electrode 8 and between the casing 1 and the end of the electrode part 9^a.

The constructions illustrated in the accompanying drawings provide a cartridge in which there is no need for a primer substance and in which the spark gaps are designed to be covered by the bulk charge of powder or principal explosive. The construction provides a casing separable from

the butt end member which may be removed to adjust or renew the electrodes. The cartridge is practically safe as compared to the usual type of cartridge having a primer 5 substance and a cap which may be set off by impact and also may be constructed readily to be absolutely water tight at its butt end.

The invention may be applied to any 10 shape of cartridge casing such as the cylindrical form illustrated in Figs. 1 and 3, and may also be adapted to the type of cartridge casing having the tapered walls such as illustrated in Figs. 4 and 5.

15 The method of discharging the cartridge will be understood from the following description. Referring to Fig. 6 the electrical circuits are shown diagrammatically as connected to the cartridge described hereinbefore. A battery is indicated at 10 and is designed to represent any source of electricity and may be a generator or magneto of any type. An induction coil is indicated at 11 and a wire 12 connects the coil with 20 electrode 8. The opposite side of the source of electricity 10 is provided with a wire 13 leading to a switch 14. From this switch 14 a choice of circuits may be had by the wire 15 leading to the second electrode 9 or 25 the wire 16 leading to the butt end member 3 which is in electrical connection with the casing 1. A switch 17 is provided in the path of the wire 13 so as to control the application of electricity to the cartridge. 30 When the switch 14 is thrown to the wire 15 there will be a single spark between the end of the electrode 8 and the curved portion of the electrode 9, as indicated by X. When the switch 14 is thrown to the wire 16 there 35 will be formed a spark between the end of the electrode 9 and the casing 1 as indicated at Y, and also a spark at X between the first and second electrode. This plurality of sparks forms an unusually effective 40 shell or cartridge design and is unusually positive in its operation.

From the previous description it will be clear that the present invention provides a sturdy and practically indestructible construction of electrically fired cartridge and also one which may be handled freely and without need of the care which must be used with the ordinary type of cartridge which may be discharged by impact. The present 50 construction also provides unusually effective firing means by the use of a plurality of the sparks in a single circuit and a construction in which the spark gap may be covered and embedded in the main charge powder 55 or explosive.

What I claim is:

1. A cartridge comprising, a tubular casing having a central bore and formed of electrically conductive material, a butt end 60 part connected to said casing, a first elec-

trode extending through said butt end part and projecting beyond the same into said bore, a second electrode spaced from said first electrode and extending through said butt end part and projecting beyond the same and curved to project across the end of said first electrode and terminating near the inner wall of said casing, and insulating material between the said electrode and between the latter and said butt end, a spark 70 gap being provided between the end of said first electrode and said second electrode and between the latter and said casing.

2. A cartridge comprising, a tubular casing of electrically conductive material having a central bore, a butt end part connected to said casing, an electrode extending through said butt end and projecting into said bore and terminating at a point adjacent the casing wall but spaced therefrom 80 to form a spark gap, and insulating material between said electrode and said butt end.

3. A cartridge comprising a tubular casing of electrically conductive material, having a central bore, a butt end part of electrically conductive material having a screw threaded connection with said casing, and an electrode extending through said butt end part and insulated from the same and terminating within said bore at a point in close proximity to said casing to provide a spark 90 gap.

4. A cartridge comprising a tubular casing of electrically conductive material having a central bore, a butt end part of electrically conductive material connected to said casing and having a tapered opening therethrough flaring inwardly into said bore, a complementary tapered plug of electrically 100 nonconductive material fitting into said tapered opening and having its smaller end farthest from said bore, and an electrode extending through said plug and projecting into said bore and terminating in close 105 proximity to said casing wall but spaced therefrom to form a spark gap.

5. A cartridge comprising a tubular casing of electrically conductive material having a central bore, a butt end part of electrically conductive material having a screw threaded connection with said casing and having a tapered opening therethrough flaring inwardly toward said bore, a complementary plug of electrically nonconductive 115 material fitting into said tapered opening and having its smaller end farthest from said bore, a first electrode extending through said plug and centrally located with respect to said casing and projecting beyond the 120 same into said bore, and a second electrode off center with respect to said first electrode, extending through said plug and projecting beyond the same and curved to project near the first electrode and terminate near the 125 130

inner wall of said casing, a spark gap being provided between said electrode within said bore and between the end of said second electrode and said casing.

6. A cartridge comprising a tubular casing of electrically conductive material having a central bore, a butt end part of electrically conductive material having a screw threaded connection with said casing and having a tapered opening therethrough flaring inwardly toward said bore, a complementary plug of electrically nonconductive material fitting into said tapered opening and having its smaller end farthest from

said bore, a first electrode extending through 15 said plug and projecting beyond the same into said bore, and a second electrode extending through said plug and projecting beyond the same and curved to project near the first electrode and terminate near the 20 inner wall of said casing, a spark gap being provided between said electrode within said bore and between the end of said second electrode and said casing.

In testimony whereof I have hereunto set 25 my hand.

HOMER HASTING.
